Primary Examiner — Khawaja Anwar*Assistant Examiner* — Julice Seung Eun Oum(74) *Attorney, Agent, or Firm* — Banner & Witcoff, Ltd.(57) **CLAIM**

The ornamental design for a foot for a weight rack, as shown and described.

DESCRIPTION

FIG. 1 is a top, front, right perspective view of a foot for a weight rack showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a top, front, right perspective view of the foot for a weight rack in FIGS. 1-7 showing a weight rack as additional example environment.

The broken lines immediately adjacent to the shaded areas define the bounds of the claimed design and form no part thereof. The broken lines depicting the weight rack in FIG. 8 show features of example environment that form no part of the claimed design.
